VACUUM CLEANER

Erik Oskar Helge Hansson and Axel Albert Forsberg, Stockholm, Sweden, assignors to Electrolux Corporation, New York, N. Y., a corporation of Delaware

Application September 19, 1938, Serial No. 230,606
In Sweden October 20, 1937

3 Claims. (Cl. 230—117)

This invention relates to vacuum cleaners and more particularly to means for supporting a motor and fan in a vacuum cleaner casing.

In vacuum cleaners of the inside bag type, a motor and fan unit is usually mounted within the vacuum cleaner casing on a horizontal axis. It is desirable to provide a resilient support for the motor and fan to reduce the transmission of noise and vibration to the outer vacuum cleaner casing.

In accordance with this invention the motor and fan are resiliently supported in a vacuum cleaner casing by a single vertical wall. It is also contemplated forming the supporting wall of non-metallic material.

What we consider to be novel and our invention may be better understood by reference to the following specification and appended claims when considered in connection with the accompanying drawing, in which

Fig. 1 is a detail sectional view of a portion of a vacuum cleaner, and

Fig. 2 is a detail sectional view of a portion of the supporting wall.

Referring to the drawing, 10 indicates a vacuum cleaner casing with an end housing 11 having an outlet opening 12. A dust bag 13 is mounted adjacent the inlet end (not shown) of the casing and a replaceable filter 14 is located in the housing 11 adjacent the outlet opening 12. A ring 15 is secured to casing 10 and is provided with an inwardly extending flange 16. Ring 15 carries end housing 11. A vertical wall 17 of non-metallic material is secured to flange 16 of ring 15 by a plurality of screws 18, only one of which is shown. Wall 17 is provided with openings 19.

A motor 20 is supported wholly by wall 17. An annular ring 21 is secured in spaced relation to wall 17 by bolts 22 and spacer sleeves 23. Motor 20 is resiliently mounted between wall 17 and ring 21 by conically shaped spiral springs 24. Three springs 24 are secured to each end of motor 20, only one of which is shown at each end. It may be found desirable in some cases to use a greater number of springs 24. The small ends of springs 24 are secured to the motor and the large ends seated in recesses 25 in the wall 17 and recesses 26 in annular ring 21. A centrifugal fan 27 is secured to the shaft 28 of motor 20. A substantially cylindrical housing 29 surrounds fan 27 and motor 20 and abuts wall 17. Opening 30 is provided in housing 29 to permit air to enter the fan 27. A plate 31 is secured to motor 20 and extends within a short distance from the

housing 29. Air leaving the fan 27 enters the space between the plate 31 and housing 29 and travels inwardly toward the motor 20. Guide vanes 32 are secured to or formed integrally with ring 21, and serve to stop the rotation of the air as it moves inwardly. A portion of the air enters openings 33 in the housing of motor 20 while the remainder of the air travels around the motor 20. The air which enters openings 33 leaves through openings 34. To prevent the dust bag 13 from sealing against the opening 30 in housing 29, a perforated bulkhead 35 is secured to the casing 10 spaced from the end of housing 29.

The wall 17, in addition to serving as a support for motor 20 and fan 27, also serves to provide electrical insulation between the motor 20 and the casing 10. The insulation of the electrical parts from the casing 10 is completed by the provision of pockets 36 and 37 in the wall 17 to receive an electrical switch 38, for controlling the operation of motor 20 and contact pins 39 for completing the connection to a source of electrical supply, as by means of a cord set having a connector engaging said contact pins. This discharge of air between the wall 17 and ring 15 is prevented by an annular gasket 40 secured between the wall 17 and flange 16. A packing 41 is secured between the pocket 36 and ring 15.

In the operation of the vacuum cleaner, rotation of the fan 27 by the motor 20 draws air through the dust bag 13 which separates from the air any dirt entrained in it. The air continues through the openings in the bulkhead 35 into housing 29 through opening 30. The air passes through the fan 27. A portion of the air travels through the motor 20 and the remainder around the motor. The air leaves the housing 29 through the openings 19 in wall 17. The air passes through the filter 14 which separates out bacteria and any fine dust or dirt, such as carbon dust from the motor brushes. The air leaves the vacuum cleaner through the opening 12 in the end housing 11.

In the use of the vacuum cleaner, the pressure varies as the cleaning operation is performed because of the variation of the sealing of the cleaning tool against the surface being cleaned. This variation in pressure may produce pulsations which result in vibrations in the motor as the motor changes in speed with the change in load imposed upon it. These vibrations if transmitted to the casing 10 may vibrate the casing and result in an audible noise. By resiliently supporting the motor 20 and fan 27 within the housing 29 and securing the complete assembly to a wall

of non-metallic material, the tendency of vibrations being transmitted to the casing 10 is greatly reduced. The danger of electrical shock by contact between the electrical parts and the casing 10 is very greatly reduced by the supporting of the motor 20 on the wall 17 and the mounting of the switch 38 and contact pins 39 in the pockets 36 and 37 of the wall 17 of non-metallic material.

What we claim is:

- 10 1. A vacuum cleaner including a casing, a wall of non-metallic material secured within said casing, a housing secured to said wall and extending within said casing, a ring located within said housing and secured to said wall in spaced relation thereto, and a motor-fan unit resiliently secured to said wall and said ring within said housing.
- 15 2. A vacuum cleaner including a casing, a ring secured to one end of said casing and having an inturned flange, a wall of non-metallic material secured to said flange and having openings, a

ring secured to said wall in spaced relationship to said wall, a motor resiliently mounted between said wall and said last-named ring, a fan carried by said motor, and a housing covering said fan and said motor and secured to said wall.

3. A vacuum cleaner including a casing; a ring secured to said casing having an inwardly extending flange, a wall of non-metallic material secured to said flange extending across said casing, having a plurality of central openings, and 10 peripheral pockets; a housing secured to said wall extending within said casing; a motor resiliently supported on said wall within said housing; a fan carried by said motor; a switch mounted in one of the pockets of said wall; and a connector 15 mounted in another of the pockets of said wall; whereby all of the electrical parts of said vacuum cleaner are insulated from the casing.
